UNITED STATES PATENT OFFICE.

JAMES MCGILLIS, OF CHIPPEWA FALLS, WISCONSIN.

SLED-PROPELLER.

No. 827,462.

Specification of Letters Patent.

Patented July 31, 1906.

Application filed September 13, 1905. Serial No. 278,321.

To all whom it may concern:

Be it known that I, JAMES MCGILLIS, a citizen of the United States, residing at Chippewa Falls, in the county of Chippewa and State of Wisconsin, have invented a new and useful Sled-Propeller, of which the following is a specification.

This invention relates to sleds, and has for its object to provide traction means for mechanically propelling the sled and in this connection to have the sled mounted upon fixed runners and to employ other movable runners to which stepping movements are imparted for engagement with the road-bed to propel the sled by the advance movements of the movable runners.

Another object of the invention is to effect the proper elevation of the moving runners when being advanced for new positions upon the road-bed and to cushion the impact of the movable runners with the road-bed so as to obviate violent pounding and consequent damage to the moving runners and other parts of the operating mechanism.

A still further object of the invention is to provide for automatically clearing accumulations of ice and snow from the movable runners, so as to prevent slipping thereof by such accumulations.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a plan view of the sled-propelling mechanism of the present invention. Fig. 2 is a side elevation thereof. Fig. 3 is a cross-sectional view on the line 3 3 of Fig. 2. Fig. 4 is a detail view of the runner-lifting device.

Like characters of reference designate corresponding parts in each and every figure of the drawings.

As exhibited in the accompanying drawings, the present sled includes a bed or body 1, supported upon a pair of fixed runners 2, there being the usual steering-bob 3 of any preferred type located at the front of the sled. Extending transversely across the un-

der side of the bed or body 1 of the rear bob are duplicate drive-shafts 4, each of which is provided, adjacent each of its ends with oppositely-disposed crank-bends 5 and 6, located, respectively, at the outer and inner 60 sides of the adjacent fixed runner 2. Each shaft is terminally mounted in bearings 7, hung from the bed 1, and between each pair of cranks the shaft has a bearing 8 through the adjacent stationary runner. Other bearings are hung from the bed or body 1 for the support of intermediate portions of the shaft.

As the construction and operation of the several movable runners is the same throughout the series of four runners, a description 70 of one of the runners is deemed sufficient. Each movable runner 10 is in the nature of a straight bar having upturned terminals and is provided about midway of its ends with a post 11, preferably in the nature of an inverted substantially U-shaped bracket bolted or otherwise rigidly secured to the top of the runner. Upon the top of this post there is secured a substantially horizontal, flat spring-bar 12, projecting forwardly and rearwardly from the post and held in place by a pair of bolts 13, piercing the spring and the top of the post. Each of the bolts rises a suitable distance above the post, so as to form a standard, with the upper end of the stand 80 ard provided with a laterally-directed head or extension 14 for a purpose as will be hereinafter described. The rear end portion of the spring is loosely connected to the adjacent crank by means of a bearing sleeve or 90 eye 15, while the front end of the spring is bent upwardly and rearwardly to form a substantially circular bow 16, which overhangs the front portion of the spring and terminates in a bearing sleeve or eye 17, receiving the adjacent crank. Upon the top of the forward portion of the spring and in advance of the eye 17 there is a rigid shoulder or abutment 18, disposed transversely across the spring. At each side of the spring and in substantial 100 parallelism therewith is a connecting-rod 19, which terminates at each end in an eye 20, loosely receiving the respective cranks, said connecting-rods operating to insure the simultaneous moving of the cranks.

A suitable motor 21 is supported upon the bed or body 1 and is provided with a power-shaft 22, carrying a sprocket-wheel 23, over which travels a sprocket-chain 24, which also engages sprockets 25 upon the middle por- 110

tions of the shafts 4, whereby the latter are simultaneously driven in the same direction.

When the sled is in operation, the pairs of movable runners are alternately elevated and moved forwardly and downwardly into engagement with the road-bed and then rearwardly by the manipulation of the cranks of the drive-shafts 4, the rearward movement of the cranks operating to push the sled forwardly against the movable runners, which are then in contact with the roadway. By having spring connections between the cranks and the movable runners the latter are cushioned when they strike the roadway, whereas by jars are absorbed and damage to the runners and the operating mechanism thereby avoided. By reason of the yieldable nature of the springs the movable runners will of course sag when the cranks begin to travel upwardly at their rear limits, whereupon the connecting-rods 19 will come into engagement with the heads 14 of the posts 13, and thereby positively lift the movable runners out of engagement with the roadway and support the same in elevated positions until the cranks begin to move downwardly at their forward limits. It will now be understood that the rods 19 have dual functions in that they connect corresponding front and rear cranks and also positively lift the movable runners from the roadway and maintain the same elevated until they are depressed at their forward limits. The reason for having the spring bowed at its front end and straight at its rear end is that the rear crank imparts a pull upon the rear portion of the spring while the front crank is pushing upon the spring and the bowed spring portion 16 gives sufficiently to prevent buckling of the spring. In other words, the spring first passes beneath the crank and then bows upwardly and rearwardly across the same and is then connected thereto, whereby when the rearward pull comes upon the extremity of the spring the lower side of the spring will be drawn up against the crank and whatever compensation is required is provided for by the bowed portion 16. When the direction of movement is reversed and the sled runs in a backward direction, there will be a pull upon the front bowed portion 16 of the spring, which will tend to break the same, and to overcome this objection the shoulder or abutment 18 has been provided in such a position as to have the adjacent crank strike the rear side of the abutment, and thereby produce a direct pull upon the spring independent of the bowed portion 16.

Each movable runner is provided upon its under side with spurs 26 to insure a positive hold upon the roadway, and the runner is also equipped with a metallic shoe 27, disposed upon its under side and provided with a longitudinal series of perforations 28, through which the spurs or projections 26 ex-

tend, each shoe exceeding in length the length of the runner and having its upturned ends 29, fixed to the respective ends of the runner. When the runner is in action, the weight of the sled forces the shoe up against the under side of the runner, so as to have the spurs extend through the openings in the shoe and engage the roadway. When the runner is lifted at its rear limit, the shoe will spring outwardly, when the pressure of the roadway is relieved therefrom, and by this movement of the shoe all accumulations of ice and snow will be stripped from the spurs or projections 26, whereby slipping of the movable runners upon the roadway is prevented. It will here be explained that each runner is maintained in contact with the roadway throughout the lower half of the rotation of the cranks by reason of the downward pressure of the adjacent spring 12, so as to secure the maximum engagement of the runner with the roadway.

To absorb the shock and jars incident to the contact of the rods 19 with the heads of the bolts 13, the under side of each head is provided with a leaf-spring 30, which has its outer end secured to a block or depending shoulder 31, carried by the under side of the head adjacent its outer end, whereby the greater portion of the spring is free to yield when struck by the adjacent rod 19.

It is proposed to have each bolt 13 passed loosely through an opening in the top of the adjacent post 11 and provided with nuts 32 above and below the top of the post for the purpose of rigidly holding the bolt in position and to enable vertical adjustment thereof, whereby the bolts may be set to lift the movable runner at different points in the rotation of the cranks, so as to accommodate the runners to rough and smooth roadways.

Having fully described the invention, what is claimed is—

1. In a traction-sled, the combination with a frame and supporting-runners connected thereto, of movable runners disposed in pairs working at opposite sides of the respective fixed runners, front and rear driving crank-shafts, operative connections between the cranks of the shafts and each movable runner, connecting-rods between corresponding cranks of the shafts, and means rising from the movable runners and overhanging the connecting-rods in the upward paths thereof to lift and support the movable runners in elevated positions during a portion of the operation of the cranks.

2. In a traction-sled, the combination with a frame and supporting-runners connected thereto, of movable runners, front and rear driving crank-shafts, posts rising from the movable runners, springs carried by the tops of the posts and connected to corresponding front and rear cranks, fastenings connecting the springs to the posts and rising above the latter with their upper ends provided with

heads, and connecting-rods extending between corresponding front and rear cranks, the heads of the fastenings lying above and in the upward paths of the connecting-rods for elevating the movable runners.

3. In a traction-sled, the combination with a frame and supporting-runners connected thereto, of front and rear driving crank-shafts, movable runners, and spring-bars carried by the runners and connected to corresponding front and rear cranks, each front spring passing beneath the adjacent crank and then bowed upwardly and rearwardly across the same with its terminal connected to the crank.

4. In a traction-sled, the combination with a frame and supporting-runners connected thereto, of front and rear driving crank-shafts, movable runners, spring-bars carried by the runners and connected to corresponding front and rear cranks, the front end portion of each front spring passing beneath the adjacent crank and then bowed upwardly and rearwardly across the same and connected to the crank, and a fixed abutment carried by the top of the front spring in front of the crank for engagement thereby when the direction of movement of the crank-shaft is reversed.

5. In a traction-sled, the combination with a frame and supporting-runners connected thereto, of front and rear driving crank-shafts, a movable runner for each pair of front and rear cranks, a post rising from each runner, a spring supported upon the top of the post and extending in front and rear thereof and terminating in eyes loosely embracing the respective cranks, the front end portion of the spring passing beneath the front crank and then bowed upwardly and rearwardly across the same, an abutment carried by the top of the spring in front of the front crank and in the path of the backward rotation thereof, a fastening piercing the top of the post and the spring and rising above the post with its upper end provided with a head, and connecting-rods extending between corresponding front and rear cranks, the heads of the fastenings lying in the up-

ward paths of the connecting-rods for lifting 50 the runners from the roadway.

6. In a traction-sled, a movable runner provided upon its under side with spurs, and spring-pressed means carried by the runner for stripping accumulations of snow and ice 55 from the spurs.

7. In a traction-sled, a movable runner provided upon its under side with spurs, and a stripping device for the spurs consisting of a bar having openings receiving the spurs 60 and provided with spring-terminals connected to the runner, the bar being intermediate free from the runner to spring downwardly therefrom and strip accumulations of snow and ice from the spurs. 65

8. In a traction-sled, the combination with a frame and supporting-runners connected thereto, of movable runners, front and rear driving crank-shafts, spring connections between each movable runner and adjacent 70 front and rear cranks, connecting-rods connecting adjacent front and rear cranks, means rising from the movable runners and overhanging the connecting-rods in the upward paths thereof to lift and support the 75 movable runners in elevated positions during a portion of the operation of the cranks, and means to cushion the impact of the rods with the means which overhang the latter.

9. In a traction-sled, the combination with a frame and supporting-runners connected thereto, of movable runners, front and rear driving crank-shafts, spring connections between each runner and adjacent front and rear cranks, connecting-rods extending between the front and rear cranks, posts rising from the runners and having heads overhanging the connecting-rods, and spring-buffers carried by the heads in the upward 85 paths of the rods. 90

In testimony that I claim the foregoing as my own I have hereto affixed my signature in the presence of two witnesses.

JAMES McGILLIS.
